UNITED STATES PATENT OFFICE.

WILLIAM SHERMAN BROWN, OF KNOXVILLE, TENNESSEE.

STEAM-ENGINE VALVE-GEAR.

REISSUED

1,100,668.

Specification of Letters Patent. Patented June 16, 1914.

Application filed May 10, 1913. Serial No. 766,876.

To all whom it may concern:

Be it known that I, WILLIAM SHERMAN BROWN, a citizen of the United States, residing at Knoxville, in the county of Knox 5 and State of Tennessee, have invented a new and useful Improvement in Steam-Engine Valve-Gear, of which the following is a specification, reference being had to the accompanying drawing.

10 My improvement relates particularly to mechanism for transmitting motion from the crank of a drive wheel of a steam locomotive to the distributing valve which admits steam to the cylinder.

15 The object of the improvement is to provide a construction which is simple, has the parts accessibly located, and which avoids irregularity of valve action due to lost motion or "pounding" at the crank.

20 This improvement is applicable to the mechanism described by my United States Patent No. 1,033,532, granted July 23, 1912, for "Steam-engine valve-gear".

In the accompanying drawings, Figure 1 25 is a side elevation, portions being broken away, showing my improvement applied to one side of a locomotive; Fig. 2 is a plan of a portion of the mechanism shown by Fig. 1; Fig. 3 is a section on the line, 3—3, of Fig. 2, looking toward the right; Fig. 4 is a section on the line 4—4, of Fig. 2, looking in the direction of the arrow; Fig. 5 is a plan of the bridge upon which the segment is seated; Fig. 6 is a side elevation of 30 said bridge. Fig. 7 is a section on the line 7—7, of Fig. 1, looking toward the left; Fig. 8 is a plan of the hanger.

Referring to said drawings, 1, is the usual valve stem extending to the distributing 40 valve (not shown). The usual horizontal, parallel cross-head guide bars, 2, are supported at their rear ends by the guide yoke extension, 3. The usual connecting rod or pitman, 4, is coupled to the usual main 45 crank, 5, carried by a drive wheel, D. On the main crank, 5, is rigidly mounted an auxiliary crank, 6, standing 90 degrees forward of the main crank. To said auxiliary crank is coupled one end of the auxiliary 50 pitman rod, 7.

A bridge, B, is located above the frame, A, and extends from the ordinary guide-yoke, 8, and guide-yoke extension, 3, to the cross beam or plate, 10, and is secured to said 55 guide-yoke and to said cross-beam by means

of bolts, 9. Said bridge is in the form of a plate having its length horizontal and being turned to bring its long edges into an upright plane. At its rear end, the bridge has a lateral extension, 11, resting against the 60 cross-beam, 10, and receiving said bolts, 9. At its forward end the bridge has a transverse extension, 12, reaching to both sides of the body of the bridge and resting against the guide yoke, 8, and the guide yoke extension, 3, and receiving said bolts, 9. The innermost of said bolts extends through the transverse extension, 12, and the guide yoke, 8, while the others of said bolts extend through the transverse extension, 12, and 65 through the guide yoke, 8, and the guide yoke extension, 3. On the outer portion of the transverse extension, 12, and integral therewith, is an ear, 13, which is directed rearward; and on the inner portion of said transverse extension is another ear, 14, also directed rearward and located horizontally opposite the ear, 13. Each of said ears has a bearing, 15, receiving the ends of a shaft 70 16. On said shaft is a bell crank or rocking member, C, preferably rotatable on said shaft, the latter being held immovably in its bearings. Said bell crank has two approximately horizontal arms, 17, and a depending arm, 18. The latter arm is coupled to 75 the valve-stem, 1. By rocking the bell crank, the valve stem is reciprocated.

An approximately upright link, 19, has its upper end coupled to the arms, 17, of the bell crank, while its lower end is coupled 80 to the forward end of the auxiliary pitman rod, 6, both ends of said link being forked to receive said rod and said arms, as shown in the drawings. Said arms, 17, are also forked to receive the upper ends of the link, 19. On the upper edge of the bridge, B, are horizontal bosses, 20. A hanger, H, has a lateral upper flange, 21, extending across the bridge, B, and secured thereto by bolts, 22, extending through said flange and the 85 bosses, 20, and horizontally through the hanger and the bridge. On said hanger is a bearing box, E. Said box receives a short rock shaft, 23, which is horizontal and transverse to the bridge and the frame, A. On the outer end of said shaft, 23, is a rocking member or arm, 24, directed upward and having on its upper end a horizontal wrist, 25. An approximately upright link, 26, has its upper end coupled to said wrist while 100 105 110

its lower end is coupled, by means of a bolt, 27, to the auxiliary rod between the link, 19, and the auxiliary crank, 6, at a point which is substantially in alinement with the axis 5 of said rock shaft, 23, when the auxiliary crank is on the upper or lower quarter, the hanger, H, bringing the axis of the rock-shaft to the proper height to effect such alinement.

10 The forward end of the auxiliary reach rod, 28, is coupled to the upper end of the rocking member or arm, 24, the forward end of the reach rod lying beside the upper end of said rocking arm and the upper end 15 of the link, 26, and the wrist, 25, extending through said three members. The rear end of said auxiliary reach rod is coupled to the upright arm, 29, which is rigid on the reversing shaft, 30, supported in bearings, 31. On said reversing shaft is an arm, 32, to which is coupled a rod, 33, which is in turn coupled to the ordinary reversing lever, 34, working on a sector or quadrant, 35.

25 In operation, the rocking arm, 24, is set to bring its upper end into any desired position in its curved path (the axis of which path is the axis of the shaft, 23), this being done by means of the reversing lever. The 30 setting of the rocking member in such position carries the upper end of the link, 26, along said curved path into the same position, and the axis of the wrist, 25, is then (and at all times) the axis of oscillation of 35 the link, 26, during the movements of the auxiliary rod. During each reciprocation, said auxiliary pitman rod rocks bodily with the axis of the bolt, 27, as a fulcrum. This involves the rising and falling of the forward end of said auxiliary rod, and during 40 such movement of said end of said rod, the link, 19, is forced up and down, and such movement of said link causes the rocking of the bell crank, C, and the reciprocation 45 of the valve stem, 1. The gear is reversed by throwing the reversing lever across the center in the usual manner, and the opening of the valve is varied by moving the upper end of the rocking member or arm, 24, 50 nearer to or farther from the upright plane in which lies the axis of the rock-shaft, 23, this being accomplished by the aid of suitable notches (not shown) on the reversing lever sector. When the upper end of the 55 rocking member or arm, 24, is on the middle of its curved path (in said upright plane), the valve motion is reduced to the extent of the "lead". The holes through which the bolts, 22, extend are larger than the diameter 60 of said bolts, in order to allow some shifting of the hanger before tightening said bolts. In this way, horizontal adjustment of the hanger and the axis of the rocking member or arm 24, may be made. Upward adjustment 65 of said axis may also be made by plac-

ing any suitable filing piece or pieces between the flange, 21, and the upper edge of the bridge.

The drawings have been copied in part from larger working drawings used in applying my improvement to a railway freight locomotive having a piston stroke of 30 inches and having a maximum valve travel of $5\frac{1}{2}$ inches and a lead of three sixteenths of an inch. The radius of the auxiliary crank, 6, (measuring from the driver axis) is 8 and $\frac{1}{2}$ inches. The distance from the auxiliary crank along the auxiliary pitman rod, 7, to the axis of the bolt, 27, is 74 and $3/32$ inches. From the latter point on said pitman rod to the link, 19, is 10 and $13/32$ inches. The length of the link, 26, is 35 and $11/16$ inches, and that, as already described, is also the length of the rocking arm, 24. The axis of the bolt, 27, is one and $5/16$ inches below the level of the driver axis and the cylinder axis (the "working line" or "center line of motion"). The length of the link, 19, is 32 inches. The height of the axis or fulcrum of the bell crank or rocking member, C, above the level of the center line of motion is 32 and $2/8$ inches. The length of the arms, 17 and 18, of the bell crank is 12 and $\frac{1}{8}$ inches. The rocking member, C, is not a true bell crank, its angle being less than ninety degrees—72 degrees.

When the engine is in forward motion and the main crank is on the back center and the auxiliary crank on the upper quarter, the arm, 17, is 2 and $\frac{1}{2}$ degrees back of a vertical line cutting the fulcrum, and the arms, 17, are 15 and $\frac{1}{2}$ degrees below a horizontal line cutting the fulcrum. When the arm, 23, is set for full valve travel (5 and $\frac{1}{2}$ inches), the forward travel of the arm, 18, from the position mentioned is 7 and $\frac{1}{2}$ degrees and the back travel of said arm from said position is 19 degrees, and the arms, 17, travel downward and upward correspondingly. Thus the larger portion of the travel of the rocking member arms is within the 90 degree angle formed by said vertical and said horizontal lines. These relative proportions and positions of the various parts 115 of the mechanism produce the desired quick movement of the valve during the opening and closing and also produce equalized travel of the valve over the port during the forward motion and during the backward motion.

It is to be observed that my improvement eliminates from the valve mechanism the eccentric and also all parts having a high velocity. No part of the valve mechanism 125 is connected to the connecting rod nor the cross-head. Movement is transmitted to the valve stem from the wrist of the auxiliary crank and said wrist travels in a relatively small circle. Thus the movement of the 130

auxiliary rod and the links, 19 and 26, are through relatively short ranges. Furthermore, it is to be noted that lost motion due to wear at the wrist of the auxiliary crank 5 will chiefly modify the lengthwise movement of the auxiliary pitman, 7, while the movement transmitted through the link, 19, is approximately at right angles to said auxiliary pitman. Hence the modification of 10 the longitudinal movement of said pitman is substantially not transmitted to said link. And it will be seen that such modification of the rocking movement of the auxiliary pitman due to wear at the wrist of the auxiliary crank will affect the link, 19, in minimized form, because the portion of the auxiliary pitman between the axis, 27, and the link, 19, is much less than between said axis and the wrist of the auxiliary crank. In 15 this connection it is to be remembered that wear by the auxiliary crank wrist in the auxiliary pitman is chiefly in the direction of the length of said pitman. Such wear produces what is termed lost motion or "pounding" at the crank.

I claim as my invention:

1. In a steam engine valve gear, the combination of a rocking member, a reversing lever in operative relation with said rocking member, an auxiliary crank, an auxiliary rod having one end coupled to said crank, an approximately upright link coupled to said auxiliary rod between its ends and at a point which is substantially in 30 alinement with the axis of said rocking member when the auxiliary crank is on the upper quarter or the lower quarter, and said link having its upper end coupled to the free portion of said rocking member, and 35 means connecting the outer end of said auxiliary rod into operative relation with the stem of the distributing valve, substantially as described.

2. In a steam engine valve gear, the combination of a rocking member extending upward from its axis, a reversing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the 50 lower quarter and said link having its upper end coupled to the free portion of said rocking member, and means connecting the outer end of said auxiliary rod into operative relation with the stem of the distributing valve, substantially as described.

3. In a steam engine valve gear, the combination of a rocking member, a reversing lever in operative relation with said rocking member, an auxiliary crank, an auxiliary rod having one end coupled to said crank,

an approximately upright link coupled to said auxiliary rod between its ends and at a point which is substantially in alinement with the axis of said rocking member when the auxiliary rod is on the upper quarter or 70 the lower quarter and said link having its upper end coupled to the free portion of said rocking member, and a bell crank in operative relation with the outer end of said auxiliary rod and with the stem of the distributing valve, substantially as described. 75

4. In a steam engine valve gear, the combination of a rocking member extending upward from its axis, a reversing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter and said link having its upper end coupled to the free portion of said rocking member, and a bell crank in operative 80 relation with the forward end of said auxiliary rod and with the stem of the distributing valve, substantially as described. 85

5. In a steam engine valve gear, the combination of a rocking member, a reversing lever in operative relation with said rocking member, an auxiliary crank, an auxiliary rod having one end coupled to said crank, an approximately upright link coupled to said auxiliary rod between its ends and at 90 a point which is substantially in alinement with the axis of said rocking member when the auxiliary crank is on the upper quarter or the lower quarter, and a bell crank having its arms at an angle of less than ninety degrees, and one of said arms being in operative relation with the outer end of the auxiliary rod and the other arm being in operative relation with the stem of the distributing valve, substantially as described. 95

6. In a steam engine valve gear, the combination of a hanger, a rocking member supported by said hanger, a reversing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described. 110

7. In a steam engine valve gear, the combination of an adjustable hanger, a rocking member supported by said hanger, a revers- 115

ing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.

8. In a steam engine valve gear, the combination of a bridge supported by the main frame, a rocking member supported by said bridge, a reversing lever, in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.

9. In a steam engine valve gear, the combination of a bridge supported by the main frame, a hanger on said bridge, a rocking member supported by said hanger, a reversing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.

10. In a steam engine valve gear, the combination of a bridge supported by the main frame, a hanger adjustable on said bridge, a rocking member on said hanger, a reversing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the

upper quarter or the lower quarter, and said link having its upper end coupled to the free portion of said rocking member, and means connecting the outer end of said auxiliary rod into operative relation with the stem of the distributing valve, substantially as described.

11. In a steam engine valve gear, the combination of a hanger, a rocking member supported by said hanger, a reversing lever in operative relation with said rocking member, an auxiliary crank, an auxiliary rod having one end coupled to said crank auxiliary rod between its ends and at a point which is substantially in alinement with the axis of said rocking member when the auxiliary crank is on the upper quarter or the lower quarter, and said link having its upper end coupled to the free portion of said rocking member, and a bell crank in operative relation with the outer end of said auxiliary rod and with the stem of the distributing valve, substantially as described.

12. In a steam engine valve gear, the combination of an adjustable hanger, a rocking member supported by said hanger, a reversing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and a bell crank in operative relation with the outer end of said auxiliary rod and with the stem of the distributing valve, substantially as described.

13. In a steam engine valve gear, the combination of a bridge supported by the main frame, a rocking member supported by said bridge, a reversing lever in operative relation with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and a bell crank in operative relation with the outer end of said auxiliary rod and with the stem of the distributing valve, substantially as described.

14. In a steam engine valve gear, the combination of a bridge supported by the main frame, a hanger on said bridge, a rocking member supported by said hanger, a reversing lever in operative relation with said

- rocking member, an auxiliary crank, an auxiliary rod having one end coupled to said crank, an approximately upright link coupled to said auxiliary rod between its ends 5 and at a point which is substantially in alinement with the axis of said rocking member when the auxiliary crank is on the upper quarter or the lower quarter, and said link having its upper end coupled to the free portion of said rocking member, and a bell crank in operative relation with the outer end of said auxiliary rod and with the stem of the distributing valve, substantially as described.
- 15 15. In a steam engine valve gear, the combination of a bridge supported by the main frame, a hanger adjustable on said bridge, a rocking member on said hanger, a reversing lever in operative relation with said rocking member, an auxiliary crank, an auxiliary rod having one end coupled to said crank, an approximately upright link coupled to said auxiliary rod between its ends and at a point which is substantially in alinement 20 with the axis of said rocking member when the auxiliary crank is on the upper quarter or the lower quarter, and said link having its upper end coupled to the free portion of said rocking member, and a bell crank in operative relation with the outer end of said auxiliary rod and with the stem of the distributing valve, substantially as described.
- 25 16. In a steam engine valve gear, the combination of a bridge, a hanger having an upper flange extending across said bridge, a rocking member on said hanger, a reversing lever in operative relation with said rocking member, an auxiliary crank, an auxiliary rod having one end coupled to said crank, an 30 approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.
- 35 17. In a steam engine valve gear, the combination of a rocking member, a reversing lever, a reversing shaft in operative relation with said reversing lever and with said rocking member, an auxiliary crank, an auxiliary rod having one end coupled to said crank, an 40 approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.
- 45 18. In a steam engine valve gear, the combination of a hanger, a rocking member on said hanger, a reversing lever, a reversing shaft in operative relation with said reversing lever and with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.
- 50 19. In a steam engine valve gear, the combination of a bridge supported by the main frame, a rocking member supported by said bridge, a reversing lever, a reversing shaft in operative relation with said reversing lever and with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.
- 55 20. In a steam engine valve gear, the combination of a bridge supported by the main frame, a hanger adjustable on said bridge, a rocking member on said hanger, a reversing lever, a reversing shaft in operative relation with said reversing lever and with said rocking member, an auxiliary crank, an auxiliary rod having one end coupled to said crank, an approximately upright link coupled to said auxiliary rod between its ends and at a point which is substantially in alinement with the axis of said rocking member when the auxiliary crank is on the upper quarter or the lower quarter, and said link having its upper end coupled to the free portion of said rocking member, and means connecting the outer end of said auxiliary rod into operative relation with the stem of the distributing valve, substantially as described.
- 60 21. A valve gear comprising, in combination, a frame, an arm supporting carried thereby, a pivoted arm carried by the sup-

port, an auxiliary connecting rod, means for transmitting motion to the rod, a connection pivoted to the rod and to the arm, and means for connecting the rod to the 5 valve for the operation thereof.

22. A valve gear comprising, in combination, a frame, an arm support carried thereby, a pivoted arm carried by the support, an auxiliary connecting rod, means for transmitting motion to the rod, a connection pivoted to the rod and to the arm, and means for connecting the rod to the valve for the operation thereof, said frame and said arm supporting being disposed for 10 relative movement and provided with means for securing them in predetermined position.

23. A valve gear comprising, in combination, a frame, an arm support carried thereby, a pivoted arm carried by the support, an auxiliary connecting rod, means for transmitting motion to the rod, a connection pivoted to the rod and to the arm, and means for connecting the rod to the valve 20 for the operation thereof, one of said frame and said arm support members being provided with an elongated aperture and the other with means engaging therewith whereby they may be secured in predetermined 25 position.

24. A valve gear comprising, in combination, a frame, an arm support carried thereby, a pivoted arm carried by the support, an auxiliary connecting rod, means for transmitting motion to the rod, a connection pivoted to the rod and to the arm, and means for connecting the rod to the valve for the operation thereof, one of said frame and said arm support members being provided 30 with a threaded bolt and the other with a threaded portion engaging therewith whereby the relative relation of the support and the frame may be varied.

25. A valve gear comprising, in combination, a frame, an arm support carried thereby, a pivoted arm carried by the support, an auxiliary connecting rod, means for transmitting motion to the rod, a connection pivoted to the rod and to the arm, and 45 means for connecting the rod to the valve for the operation thereof, said frame and said arm support members being provided with means for varying their relation vertically.

26. A valve gear comprising, in combination, a frame, an arm support carried thereby, a pivoted arm carried by the support, an auxiliary connecting rod, means for transmitting motion to the rod, a connection 50 pivoted to the rod and to the arm, and means for connecting the rod to the valve for the operation thereof, said frame and said arm support members being provided with means for varying their relation horizontally. 60

27. A valve gear comprising, in combination, a frame, an arm support carried thereby, a pivoted arm carried by the support, an auxiliary connecting rod, means for transmitting motion to the rod, a connection pivoted to the rod and to the arm, and means for connecting the rod to the valve for the operation thereof, said frame and said arm support members being provided with interposed means for varying 70 their relation vertically. 75

28. A valve gear comprising, in combination, a pivoted arm, an auxiliary connecting rod, means for transmitting motion to the rod, a connection pivoted to the rod and to the arm, and means for connecting the rod to the valve for the operation thereof. 80

29. A valve gear comprising, in combination, a movable support, means in operative relation thereto for moving the support, an auxiliary rod, means for transmitting motion to the rod, a connection pivoted to the rod and forming a fulcrum therefor, and pivoted to the support, means for connecting the rod to the valve for the operation thereof, and means for varying the position of the fulcrum vertically. 85 90

30. A valve gear comprising, in combination, a movable support, means in operative relation thereto for moving the support, an auxiliary rod, means for transmitting motion to the rod, a connection pivoted to the support, means for connecting the rod to the valve for the operation thereof, and means for varying the position of the fulcrum vertically relatively to a horizontal line coincident with the axis of the means for transmitting motion. 95 100

31. A valve gear comprising, in combination, a movable support, means in operative relation thereto for moving the support, an auxiliary rod, means for transmitting motion to the rod, a connection pivoted to the rod and forming a fulcrum therefor, and pivoted to the support, means for connecting the rod to the valve for the operation thereof, and means for varying the position of the movable support vertically. 105 110

32. A valve gear comprising, in combination, a movable support, means in operative relation thereto for moving the support, an auxiliary rod, means for transmitting motion to the rod, a connection pivoted to the rod and forming a fulcrum therefor, and pivoted to the support, means for connecting the rod to the valve for the operation thereof, and means for varying the position of the movable support vertically relatively to a horizontal line coincident with the axis of the means for transmitting motion. 115 120

33. A valve gear comprising, in combination, a movable support, means in operative relation thereto for moving the support, an auxiliary rod, means for transmitting motion to the rod, a connection pivoted to the 125 130

rod and forming a fulcrum therefor, and pivoted to the support, means for connecting the rod to the valve for the operation thereof, and means for varying the position 5 of the movable support horizontally.

34. A valve gear comprising, in combination, a movable support, means in operative relation thereto for moving the support, an auxiliary rod, means for transmitting motion to the rod, a connection pivoted to the rod and forming a fulcrum therefor, and pivoted to the support, means for connecting the rod to the valve for the operation thereof, and means for varying vertically 10 the pivot point of said support on said connection relatively to said fulcrum.

35. A valve gear, comprising, in combination, a movable support, means in operative relation thereto for moving the support, an auxiliary rod, means for transmitting motion to the rod, a connection pivoted to the rod and forming a fulcrum therefor and pivoted to the support, means for connecting the rod to the valve for the operation thereof, and means for varying horizontally the 15 pivot point of said support on said connection relatively to said fulcrum.

36. A valve gear comprising, in combination, a frame provided with an arm support 20 movable relatively thereto, an upwardly disposed rocker arm pivoted in said support, means for moving the upper end of said arm, an auxiliary rod, means for transmitting motion to the rod, a fulcrum link pivoted to the rod and to the upper portion of the rocker arm, a pivoted bell crank for operating the valve, a connecting link for transmitting motion from the rod to the bell 25 crank, and means for varying the relation of the pivot point of said rocker arm and fulcrum link relatively to the pivot point of 30 said bell crank.

37. A valve gear comprising, in combination, a frame provided with an arm support

link relatively to the pivot point of said bell crank.

37. A valve gear comprising, in combination, a frame provided with an arm support movable relatively thereto, an upwardly disposed 45 rocker arm pivoted in said support, means for moving the upper end of said arm, an auxiliary rod, means for transmitting motion to the rod, a fulcrum link pivoted to the rod and to the upper portion of 50 the rocker arm, a pivoted bell crank for operating the valve, a connecting link for transmitting motion from the rod to the bell crank, and means for varying the relation of the rocking axis of said rocker arm relatively to the pivot point of said bell crank.

38. A valve gear comprising, in combination, a frame provided with an arm support movable relatively thereto, an upwardly disposed rocker arm pivoted in said support, 60 means for moving the upper end of said arm, an auxiliary rod, means for transmitting motion to the rod, a fulcrum link pivoted to the rod and to the upper portion of the rocker arm, a pivoted bell crank for operating the valve, a connecting link for transmitting motion from the rod to the bell 65 crank, and means for varying the relation of the pivot point of said rocker arm and fulcrum link relatively to the pivot point of 70 said bell crank.

In testimony whereof I have signed my name, in presence of two witnesses, this eighth day of May, in the year one thousand nine hundred and thirteen.

WILLIAM SHERMAN BROWN.

Witnesses:

CYRUS KEHR,
N. N. BAYDEN.
